UNITED STATES PATENT OFFICE

ROY E. FLEEK, OF OIL CITY, PENNSYLVANIA

AUTOMOBILE SIGNAL

Application filed October 5, 1928. Serial No. 310,544.

This invention relates to a directional signal for motor vehicles and the like, the general object of the invention being to provide means for indicating when the vehicle is to stop or is to be turned to the right or left.

5 A further object of the invention is to provide a casing having a plate in its front stenciled with upper and lower groups of characters, the upper group forming the composite word "Stop" and "Turning" and the lower group forming the composite word "Right" and "Left", with means within the casing and including electric lamps, so arranged that when one circuit is closed the characters forming the word "Stop" will be illuminated and when the second circuit is closed, the characters forming the words "Turning right" will be illuminated and when the third circuit is closed, the characters forming the words "Turning left" will be illuminated.

10 A further object of the invention is to provide the device with the ordinary tail light.

This invention also consists in certain other features of construction and in the combination and arrangement of the several parts, to be hereinafter fully described, illustrated in the accompanying drawings and specifically pointed out in the appended claim.

15 In describing the invention in detail, reference will be had to the accompanying drawings wherein like characters denote like or corresponding parts throughout the several views, and in which:—

20 Figure 1 is a front view of the device.

Figure 2 is a vertical sectional view taken immediately in rear of the stenciled plate.

Figure 3 is a vertical sectional view taken immediately in rear of the first chambered plate.

25 Figure 4 is a rear view of the second chambered plate.

Figure 5 is a top plan view, with the top of the casing broken away.

30 Figure 6 is a section on line 6—6 of Figure 2.

Figure 7 is a section on line 7—7 of Figure 2.

35 Figure 8 is a section on line 8—8 of Figure 1.

Figure 9 is a view showing the "Turning right" signal illuminated.

Figure 10 is a view showing the signal "Turning left" illuminated.

Figure 11 is a view showing the "Stop" 55 signal illuminated.

Figure 12 is a diagrammatic view of the circuits.

In these views, the numeral 1 indicates the casing of the device which is adapted to be fastened to any suitable part of a motor vehicle or the like at the rear thereof, said casing having its ends stepped, as shown, so that the upper part of the casing is longer than its central portion and the central portion is longer than the lower portion. This reduced lower portion forms a chamber for the tail lamp 2 and the front of this chamber is closed by the usual red lens 3. The front of the casing above the tail lamp part 70 is open and a transparent plate 4 covers the opening. A stenciled plate 5 rests against the rear face of the transparent plate, and this plate 5 is stenciled with upper and lower groups of characters, the upper group 6 forming either the word "Stop" or the word "Turning" and the lower group 7 forming either the word "Right" or the word "Left". A plate 8, having the partitions 9 thereon, is placed in the casing with the free edges of 80 the partitions engaging the stenciled plate 5, and a second plate 10, having the partitions 11 thereon, is placed in the casing with the edges of its partitions engaging the rear of the plate 8. Spaces 12 are placed between 85 the rear of this plate 10 and the rear cover plate 13 of the casing so as to form a chamber A at the rear of the casing. The partitions 11 on the plate 10 form two chambers B and C, the chamber C being below the 90 chamber B, with one chamber extending beyond the end of the other chamber and the two chambers being in communication with each other through the small opening 11'.

A chamber D is formed between the plates 95 8 and 10 by the end partitions 11 and the walls of the casing 1. At the opposite end of the casing, the plate 10 extends a short distance into the top step of the casing, while this end of the plate 8 has an opening 14 100

therein so that a lateral extension A' of chamber A is formed at the left hand end of the casing which places this chamber A in register with the character S of the upper group of characters 6. The top parts of both the plates 10 and 8 and their upper partitions are recessed to form the passage 15 which places the chamber A in communication with an arc-shaped slot 16 formed in the stenciled plate 5 over the character "U" in the upper group of characters 6 so as to form the character "O" when this slot and the "U" forming slot are illuminated.

The rear part of the plate 10 between the passage 15 and the left hand end of the plate is rounded, as shown at 17, and a lamp 18 is placed on this rounded portion so that the rays of light therefrom will pass through the extension A' and through the passage 15 to illuminate the character "S" and the slot 16.

Electric bulbs 19 are carried by the plate 10 on the front face of the plate, some of these bulbs being designated at R, others being designated L and one of the bulbs being designated S. As will be seen, there are three bulbs in chamber B designated R, S and L respectively and there are two bulbs in the chamber C designated respectively R and L and there are also two bulbs in chamber D designated R and L respectively. The R bulb in chamber B is placed partly in the passage 11'. As shown in Figure 12, the bulb S in chamber B and the bulb 18 in chamber A are arranged in a circuit a. The three L bulbs are arranged in a circuit designated by the letter b and the three R bulbs are arranged in a circuit indicated at c. A switch 20 is arranged in each circuit. If desired, this switch may be a three-way one. This Figure 12 also shows the circuit d containing a switch 21 for the tail lamp 2. The conductors for these bulbs pass through an opening 22 formed in the rear cover plate 13 and are connected with the battery of the car or other suitable source.

The partitions 9 on plate 8 divide the same into the chambers E and F and into a small L-shaped chamber G which projects into the chamber E. The plate 8 is formed with an opening 23 arranged immediately above the upper end of the partitions forming the chamber G and this opening is directly in front of the R lamp in chamber B. A second opening 24 is arranged in the right hand end of the chamber E and is located in front of the R lamp in chamber C. A pair of openings 25 is formed in plate 8 in chamber F and one of these openings is in front of the L lamp in chamber D and the other is in front of the R lamp in said chamber D. The plate 8 is also formed with the slots or openings 26 which are of respective T, U and P shape and these openings communicate with the chamber B and they are in alignment with

the characters T, U and the P forming part of the composite character "PR" on the stenciled plate 5. The slot 27 in said plate 5 which converts the P into an R is arranged in the left hand extension F' of the chamber 70 F and the characters "NING" are in communication with said chamber F. An L-shaped slot 28 is formed in plate 8 and places the chamber G in communication with the chamber C and this slot 28 is in alignment 75 with the character L in the lower group of characters 7 on the stenciled plate. The vertical slot 29 in the stenciled plate, arranged adjacent the character L therein, is in communication with the chamber E. The plate 8 80 is formed with the one vertical and two horizontal slots 30 which are arranged in the right hand end of the lower part of chamber E and these slots are in communication with the chamber C. A block 31 is arranged on the plate 8 and engages the stenciled plate and is located between the horizontal slots 30 and an opening 32 passes through the block and the plate 8 and is in communication with the chamber C and has its front end registering with a slot 33 in the stenciled plate which forms a part of the composite character "EG" and is used to form the letter "E" when the "Left turning" signal is being used. An angle shaped slot 34 also forms 95 part of this composite character and is in communication with the right hand part of chamber E and forms the letter G when the "Right turning" signal is being used.

A vertical slot 35 and a short horizontal slot 36 are formed in plate 8 in the right hand part of chamber E and communicate with chamber G, and these slots are in register with the first part of the composite letter "HF" in the lower group of characters on the stenciled plate, the rear part of this composite character being in communication with the chamber E. A block 37 is arranged in the right hand part of chamber E in plate 8 and a slot 38 passes through this block and through the plate 8 and is in communication with the chamber C and this slot 38 is in register with a slot 39 formed in the stenciled plate between the upper ends of the two parts of the character 26 in the group 7. The character "T" of this group is in communication with the lower part of the chamber F.

From the foregoing it will be seen that when the switch 20 in circuit a is closed, current will pass to the lamp 18 on the rear part of the plate 10 and to the S lamp in chamber B so that the rays of light from lamp 18 will pass through the extension A' of chamber A and thus illuminate the character "S" of the upper group of characters on the stenciled plate 5 and some of the rays of light from this lamp will pass through the passage 15 and through the arc-shaped slot 16 in the stenciled plate. The rays of light from the 130

"S" lamp in chamber B will pass through the slots 26 which form respectively the letters "T", "U" and "P" and through the characters "T", "U" and "P" on the stenciled plate, so that the word "Stop" will be illuminated, 5 the rays of light passing through the slot 16 converting the "U" into an "O" and as the slot 27 in the stenciled plate is out of alignment with the chamber E, no rays of light will pass through this slot, so that the character "P" is formed. Thus the "Stop" signal will be given. When the circuit *d* is closed, the three L lamps will be lighted and the rays of light from the L lamp in chamber B will 10 pass through the slots 26 and the registering character forming slots in the stenciled plate so as to illuminate the letters "T", "U" and "P", while the rays of light from the L lamp in chamber D will pass through one of the openings 25 into the chamber F and will pass 15 through the slot 27 in the stenciled plate, thus completing the illumination of the letter R and also illuminating the letters "NING", so that the word "Turning" is formed. The rays of light from the L lamp in chamber C 20 will pass through the slot 28 and the character L on the stenciled plate and some of the rays of light from this lamp will pass through the slots 30 as well as the hole 32, thus illuminating the E character, and some 25 of the rays of light from this lamp will pass through the slots 25, 36 and 38, thus illuminating the F character and the T character will be illuminated by the rays of light from 30 the L lamp in chamber D passing into chamber F and through the T character. Thus the word "Left" is illuminated in the lower group of characters, so that the complete signal will read "Turning left".

When the circuit *e* is closed, the R lamps 40 will be lighted, which will illuminate the word "Turning" in the first group of characters, as before described, and some of the rays of light from these lamps will pass through the openings 23, 24 and 25 in the plate 45 and illuminate the characters forming the word "Right" in the lower group of characters, thus giving the signal "Turning right". As will be seen, this invention will give the three signals "Stop", "Turning 50 right" and "Turning left", with a casing of comparatively small size and of few parts so that the device will present a neat and attractive appearance and will not be awkward 55 in size, as it would be if the signal words were arranged separately.

It is thought from the foregoing description that the advantages and novel features of the invention will be readily apparent. 60 It is to be understood that changes may be made in the construction and in the combination and arrangement of the several parts, provided that such changes fall within the scope of the appended claim.

65. What I claim is:—

A direction signal comprising a casing having an open front and provided with the ends thereof stepped to form the casing into portions of different lengths, a stencilled plate bearing direction characters closing the 70 casing and having letters "STORNING" for the upper compartment, and letters "RLIGHT" for the lower compartment, a dividing plate in said casing to provide a front chamber, partitions carried by the dividing plate and abutting the stencilled plate to divide the chambers into compartments arranged one above the other and one partition having an opening to establish communication between said chambers, a second dividing 75 plate in the casing providing intermediate and rear chambers, spacing elements between the second dividing plate and the rear wall of the casing, partitions on the second dividing plate bearing against the first dividing plate 80 to provide a plurality of lamp compartments, lamps in said compartments, said first dividing plate having light openings establishing communication between the compartments of the intermediate and front chambers to 85 permit illumination of the characters by the lamps, said rear chamber extending about one of the ends of the intermediate and front chambers and having one of the characters disposed in front thereof, and a lamp 90 in the rear chamber, whereby the words Turning or Stop may be selectively displayed from the upper compartment and Right or Left from the lower compartment.

In testimony whereof I affix my signature. 100
ROY E. FLEEK.
